(57) **CLAIM**

The ornamental design for an electric vehicle charging station as shown and described.

DESCRIPTION

FIG. 1 is an elevated front side perspective of an electric vehicle charging station in accordance with an embodiment; FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

Broken lines or phantom lining are used for illustrative purposes only, and form no part of the claimed design. Any shading in the drawings is also used for illustrative purposes to provide contrast and forms no part of the claimed design.

1 Claim, 7 Drawing Sheets
